US00D361752S

United States Patent [19]

Yamaga

[11] Patent Number: Des. 361,752

[45] Date of Patent: ** Aug. 29, 1995

[54] WAFER BOAT OR RACK FOR HOLDING SEMICONDUCTOR WAFERS

[75] Inventor: Kenichi Yamaga, Sagamihara, Japan

[73] Assignees: Tokyo Electron Kasbushiki Kaisha, Tokyo; Tokyo Electron Tohoku Kabushiki Kaisha, Esashi, both of Japan

[**] Term: 14 Years

[21] Appl. No.: 13,079

[22] Filed: Sep. 17, 1993

[52] U.S. Cl. D13/182

[57] CLAIM

The ornamental design for wafer boat or rack for holding semiconductor wafers.

DESCRIPTION

FIG. 1 is a front elevational view of a wafer boat or rack for holding semiconductor wafers showing my new design;

FIG. 2 is a rear elevational view thereof;

FIG. 3 is a right side view thereof, the left side view being a mirror image and, therefore, not being shown;

FIG. 4 is a top view thereof;

FIG. 5 is a bottom view thereof;

FIG. 6 is an enlarged sectional view on section 6—6 in FIG. 1; and,

FIG. 7 is an enlarged sectional view of on section 7—7 in FIG. 1.

FIG. 1

FIG. 3

FIG.5

FIG.4

FIG.2

FIG. 6

FIG. 7
